CAP FOR CONTAINERS

Morton B. Stull, Boonton, N.J. (2% Stull Engraving Co.,
221-223 Banta Ave., Garfield, N.J.)

Filed July 5, 1962, Ser. No. 70,805

Term of patent 14 years

(Cl. D58—26)

Fig. 1

Fig. 2

Fig. 3

Fig. 4

I claim:

The ornamental design for a cap for containers, as shown.
